(57) CLAIM

The ornamental design for a ballet shoe as shown and described.

DESCRIPTION

FIG. 1 is a perspective view of an embodiment of our new design of a ballet shoe, in which the outsole patch is hatched using the USPTO using the convention of dashed vertical lines for purple or violet (e.g., Pantone 228-Pantone 275, any one of Pantone 511-Pantone 531, any one of Pantone 663-Pantone 669, any one of Pantone 681-Pantone 690, Pantone 807, Pantone 813 or Pantone 814, any one of Pantone 2395-Pantone 2695, Pantone 2715, Pantone 2725, any one of Pantone 2735-Pantone 2746, any one of Pantone 5115-Pantone 5315, or any one of RAL 4001-RAL 4012); FIG. 2 is a first side view of the design of FIG. 1; FIG. 3 is a second side view of the design of FIG. 1; FIG. 4 is a top view of the design of FIG. 1; FIG. 5 is a bottom view of the design of FIG. 1; FIG. 6 is a front view of the design of FIG. 1; and, FIG. 7 is a back view of the design of FIG. 1.

The broken lines in the figure views depict portions of the ballet shoe that form no part of the claimed design.
